United States Patent Office.

EDWARD G. FAST, OF WASHINGTON, DISTRICT OF COLUMBIA.

Letters Patent No. 98,859, dated January 18, 1870.

IMPROVED TRAVELLING SLEEPING-CUSHION.

The Schedule referred to in these Letters Patent and making part of the same.

I, EDWARD G. FAST, of Washington, in the District of Columbia, have invented an apparatus, the object of which is to promote the comfort of passengers in railroad-cars, steamboats, stages, or vehicles of any description, by providing a suitable support for the head and the upper part of the spine, where the backs of the seats are too low to secure it. This comfort is especially adapted to ladies, as it precludes all danger of disarranging their hair-dresses.

In cases of emergency, this apparatus, when consisting of an air-cushion, can be used as a life-preserved.

The peculiarity of the invention consists of the combination of an air-cushion of nearly semicircular form, and a strap, the latter consisting of two parts, joined together, so as to shorten or lengthen it at convenience. Instead of an air-cushion, any other cushion bent to the above form can be used.

The apparatus is worn around the neck, the head of the wearer reclining at the back upon the cushion.

In the connected straps, the under parts of the arms are held horizontally, the natural weight of which gives a proportionate balance for the support of the head.

Description of the Accompanying Drawings.

In the enclosed drawings—

A is the cushion.

B and C, the two parts of the strap.

Figure 2 shows the mode of using the apparatus.

Claim.

I claim, as my improvement—

The semicircular cushion (air-cushion, of India rubber, or stuffed) A, constructed as herein described, and provided with the strap B C, for the purpose specified.

EDWARD G. FAST.
